Attorney

UNITED STATES PATENT OFFICE.

HENRY N. JOHANNS, OF DENVER, COLORADO.

DUSTLESS ASH REMOVER.

Application filed November 17, 1922. Serial No. 601,588.

To all whom it may concern:

Be it known that I, HENRY N. JOHANNS, a citizen of the United States, residing in the city and county of Denver and State of Colorado, have invented certain new and useful Improvements in Dustless Ash Removers; and I do declare the following to be a full, clear, and exact description of the invention, such as will enable others skilled in the art to which it appertains to make and use the same, reference being had to the accompanying drawings and to the characters of reference marked thereon, which form a part of this specification.

15 This invention relates to a device especially well adapted for removing ashes from furnaces.

It is well known that when ashes are removed from the ash pit of a furnace by 20 means of an ordinary shovel and deposited in an ash can or pail, that a large quantity of dust will be liberated which causes considerable annoyance.

It is the object of this invention to provide a device that shall be so designed and constructed that the ashes can conveniently be removed from the furnace and carried to the outside ash pit without liberating any dust, fumes or heat.

30 My invention briefly described, consists of a container having a flat bottom and having all sides and one end closed, a hinged member being provided at the open end for closing the container after it has been filled 35 with ashes in the manner hereinafter described.

In order to more fully and clearly describe my invention I shall have reference to the accompanying drawing which shows the preferred embodiment thereof; and in which 40

Fig. 1 shows the base portion of a furnace with part of the ash pit sides broken away so as to better show the manner of using my device.

45 Fig. 2 shows my improved ash remover in closed position, which position it occupies while carrying the same.

Fig. 3 is a perspective view of my device.

Fig. 4 is an end view of the same looking 50 in the direction of arrow 4 in Fig. 1; and

Fig. 5 is a section taken on line 5—5, Fig. 4.

55 The same reference characters will be employed to indicate the same parts throughout the several views.

Numeral 1 indicates the ash pit of a furnace and 2 the ashes therein, while 3 indicates the opening into the ash pit. I have shown my ash remover 4 in the position which it occupies in removing the ashes from 60 the pit. My ash remover consists of a container having a bottom member 5 which is flat and substantially rectangular in shape. To the sides of the bottom member I secure a cover member 6 which is centrally curved 65 and forms with the bottom a semi- or substantially semi-circular housing, one end of which is closed by a member 7 to which I secure a handle 8. The other end of the housing is preferably open and cut on an upwardly and rearwardly extending angle with respect to the plane of the bottom, as clearly shown in Figs. 1 and 2. To the front edge of bottom 5 I hinge a cover member 9 which can be rotated into the position shown in Figs. 1 and 3 or into the closed position shown in Fig. 2. An eyelet 10 is secured to the inner surface of cover 10 and secured to this is a rod 11 which extends rearwardly through the housing and terminates in a handle 12. A metal washer 13 is secured to end plate 7 and has a central tubular hub 14 through which the rod 11 extends. It is evident that if the rod 11 is moved to the right, or rearwardly, the cover 70 75 80 85 90 95 100 105 110

In using my ash remover I open the cover 9 to the position shown in Fig. 3 and insert the same through the ash pit door in the manner shown in Fig. 1. When the remover housing is partly filled with ashes, I pull the handle 12 rearwardly. This closes 95 the cover and forces the ashes into the housing. The cover is then opened and the ash remover shoved farther into the ashes and the operation repeated if necessary until the housing is full. The cover 9 is then closed and held in closed position while the ashes are carried to the outside ash pit where they are dumped by opening the cover in a manner clearly apparent.

Although I have shown the ash remover as formed with a flat bottom and curved top, it is evident that it may be made of rectangular cross section or of any cross section desired. It is considered quite essential, however, to have the bottom flat as 110

otherwise it will be more difficult to fill the same with ashes.

Having now described my invention, what I claim as new is:

5. 1. An ash remover consisting of a housing having one substantially flat side forming the bottom thereof, one end of said housing being open and the other closed, a cover hingedly connected to the flat side at the 10 open end and means extending through the housing for opening and closing said cover.
2. An ash remover consisting of a tubular housing having one substantially flat side forming the bottom thereof, having one end 15 closed, a cover hinged to the flat side adapt-

ed to open and close the open end of the housing and a rod passing through the housing and hingedly connected to the cover whereby the latter may be opened and closed by reciprocating the rod.

3. An ash remover comprising in combination a hollow housing having one flat side forming the bottom thereof, one closed end, means hinged to the flat side for closing the other end and for assisting in filling the 20 25 housing with ashes.

In testimony whereof I affix my signature.

HENRY N. JOHANNS.
